 Metal Mouldings Corporation, Detroit, Mich.,
 a corporation of Michigan

Application September 29, 1937, Serial No. 166,386

2 Claims. (Cl. 153—40)

This invention relates to apparatus for bending metal and particularly to apparatus that is adapted to bend strips of sheet metal of various cross-sectional configurations into a predetermined shape.

Objects of the invention include the provision of apparatus for bending strips of sheet metal of non-planular cross-sectional configuration into predetermined shape without causing a buckling of the metal; to provide mechanism by means of which flanged sheet metal strips may be bent into predetermined shapes; to provide apparatus of the type described including a rotatable die member having a peripheral contour corresponding with the shape of the desired finished article and peripherally shaped to accommodate the cross-sectional configuration of the strips desired to be bent, together with means for yieldably clamping the strips against the peripheral surface of the member while the member is rotating whereby to cause the strips to assume the form of the peripheral surface of the member and yet maintain the strip against deformation from its intended cross-sectional configuration; to provide apparatus of the type described in which those portions of the strip being formed and lying in a plane radial to the direction of rotation of the member are yieldably maintained between radially directed surfaces preventing deformation of the cross-sectional configuration of the strip from its intended form; the provision of an apparatus of the type described in which rigid means having a surface conforming at least in part to the cross-sectional configuration of the strip to be formed is yieldingly pressed against the surface of the strip so as to maintain it in a radial direction against the periphery of the rotatable member whereby to cause it to conform to the peripheral shape of the rotatable member; the provision of an apparatus as above described in which the radially yieldable pressure member is so constructed and arranged as to advance and retract with respect to the axis of rotation of the rotatable member where such peripheral surface is of eccentric relation with respect to the axis of rotation of the rotatable member, or in which the distance from the axis of rotation of the rotatable member to various portions of its peripheral surface vary around the periphery; the provision of a construction as last described in which the radially yieldable member exerts a constant pressure against the strip to be formed to maintain it against the periphery of the rotatable member; to provide apparatus of the type de-

scribed including fluid actuated pressure exerting parts adapted to yieldingly maintain the strips being acted upon in proper cooperation with respect to the periphery of the rotatable member; and in general to provide an apparatus of the type described that is simple in construction, economical to manufacture, and efficient in use.

The above being among the objects of the present invention the same consists in certain novel features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Figure 1 is a partially broken, vertical sectional view taken centrally through a power bending machine;

Fig. 2 is a reduced top plan view of the machine shown in Fig. 1;

Fig. 3 is a horizontal sectional view taken on the line 3—3 of Fig. 1;

Fig. 4 is a side elevational view of a completed article such as produced by the machine illustrated in the previous views; and,

Fig. 5 is an enlarged transverse sectional view taken on the line 5—5 of Fig. 4 illustrating the cross-sectional configuration of the particular article illustrated as being produced on the machine shown in the previous views.

While the present invention is applicable for use in the bending of metal strips of any cross-sectional configuration to a predetermined completed shape, it is particularly adapted for the bending of non-planular sheet metal strips. By non-planular sheet metal strips is meant particularly sheet metal strips provided with flanges, beads, grooves or other portions offset from the plane of the main body portion thereof. As is well recognized in the art the problem of bending the strips of such cross-sectional configuration offers a considerable problem in that in bending such strips out of a straight form those portions of the strip extending out or away from the plane of the main portion of the strip have a tendency to distort out of their desired position with respect to the main body portion and to become wrinkled or otherwise displaced from their proper and desired relationship with respect to the main body portion. Particularly where all or most of one surface of the strip is

adapted to be exposed to view in service and particularly where employed as a finishing or garnishing strip it is important that the exposed surfaces be smooth and true to form otherwise an unsightly article results. While there are a large number of instances where articles of curved or of irregular shape are formed from strips of metal having a cross-sectional configuration as above generally described, the garnish moldings employed in the bodies of automobiles around the window openings and in other locations are a good example of articles of the type under discussion and, accordingly, for the purpose of illustration only the form of the apparatus shown in the accompanying drawings has been designed to form a garnish molding for a rear quarter window of an automobile body, the particular shape and section of which is illustrated in Figs. 4 and 5, respectively.

Referring to Figs. 4 and 5 and particularly to Fig. 4, it will be noted that the garnish molding there indicated generally at 10 includes two sides 12 and 14 which are straight for the greater portion of their length and are joined together in perpendicular relationship to each other by a portion 16 of relatively sharp curvature. The remaining end portions of the sides 12 and 14 are curved as at 18 and 20, respectively, and are joined to opposite end portions of a curved portion 22 of relatively generous curvature, the whole forming a closed loop. It will be understood by those skilled in the art that the garnish molding 10 is arranged on the inner side of a window opening in an automobile and that the inner face thereof overlies the margins of the interior finish (not shown) surrounding the window opening to which the garnish molding 10 is to be adapted. While, as previously explained, such garnish molding may have different cross-sectional configurations, all of them are usually made from sheet metal and usually include one or more flanged edge portions directed at an angle to the plane of the main body portion of the molding, and/or beaded or other similarly offset portions. As a matter of illustration it is assumed that the garnish molding 10 is of a cross-sectional configuration such as shown in Fig. 5 and in which it will be noted that it includes the main body portion 24 of generally planular conformation having oppositely directed flanges 26 and 28 at opposite marginal edges thereof. The main body portion 24 is also provided with a bead 30 on one face thereof extending in parallelism to the flange 26 and slightly spaced therefrom and which bead 30, due to its method of formation as by rolls or other conventional means, forms a complementary groove 32 in the opposite face of the main body portion 24. It will be readily apparent that any attempt to bend a strip of metal of the cross-sectional configuration illustrated in Fig. 5 about a line parallel to the plane of the main body portion 24 and perpendicular to the plane of the flanges 26 and 28 would necessitate the stretching of the metal in one of the flanges 26 or 28 and compression of the metal in the other thereof, the latter flange in particular having a tendency to ripple or wrinkle during such operation, the bead 30 having a tendency to flatten out, and the metal of the main body portion 24 adjacent each of the flanges 26 and 28 having a tendency to distort out of its true and desired form. By the use of the apparatus constituting the present invention such bending of a member having a cross-sectional configuration such as

that shown in Fig. 5 may be accomplished without distorting or otherwise affecting the cross-sectional configuration of the strip, resulting in a final product that is smooth, devoid of defects, and of a character capable of enhancing the appearance of the automobile to which it is applied.

Referring to the drawings and particularly to Fig. 1 it will be noted that the apparatus comprising the present invention includes a suitable table 30 of rigid construction provided with suitable legs or supports 32 by means of which it may be suitably supported from a floor or the like. Adjacent one end of the table and rotatably supported by suitable bearings 34 therein in a vertical hollow shaft 36 which projects both above and below the table 30. The table 30 immediately surrounding the shaft 36 is thickened on its lower surface as at 38 and secured to the lower face of the thickened portion 38 as by screws 40 is a spider 42 which carries centrally thereof an additional bearing 44 for the shaft 36. Secured to the lower face of the spider 42 by the same screws 40 that secure the spider 42 to the table 30 is a drum-like housing 46 having its closed lower end apertured for passage of the shaft 36 therethrough and provided with an additional bearing 48 therefor. The bearings 34, 44 and 48 cooperate to prevent axial movement of the shaft 36 with respect to the table. Within the housing 46 a worm wheel 50 is non-rotatably secured to the shaft 36.

As best illustrated in Fig. 3 a horizontally extending shaft 52 is projected through a side of the housing 46 and is rotatably supported therein by means of suitable bearings 54. Within the housing 46 the shaft 52 is provided with a worm 56 which lies in meshing relationship with respect to the worm wheel 50. One projecting end of the shaft 52 is provided with a pulley 58 for the purpose of permitting the shaft to be driven thereby. An electric motor 60 is suitably supported from one of the supports 32 through a hinged connection 62 as indicated in Fig. 3 and its drive shaft 64 is provided with a pulley 66 aligned with the pulley 58 and drivingly connected thereto by means of a plurality of belts 68. It will thus be understood that rotation of the motor shaft 64 will cause a corresponding rotation of the shaft 52, worm 56, worm wheel 50 and shaft 36. The hinged connection 62 will be recognized as a standard form of motor mounting arranged to permit the weight of the motor 60 to maintain the belts 68 in taut condition.

It will be noted from an inspection of Fig. 3 that the shaft 52 is provided with a conventional form of solenoid brake indicated generally at 70 arranged to be freed when its solenoid 72 is energized simultaneously with the motor 60 and adapted to set the brake through the spring 74 when the motor 60 is de-energized, thus permitting the shaft 36 to be brought to a condition of rest quickly upon opening the circuit to the motor 60.

Suitable means such as the passages 76, 78 and 80 formed in the table 30 and its extension 38 are provided for the introduction of lubricant to the bearings 34 and 44. The housing 46 is adapted to maintain a supply of lubricant in its lower portion for lubrication of the worm wheel 50 and worm 56 as well as for the bearings 48. Lubricant is prevented from escaping downwardly between the shaft 36 and the housing 46 by means of suitable seals 82 provided around the shaft 36 in the lower end of the housing 46.

An air cylinder indicated generally at 84 is relatively non-rotatably secured to the lower end of the shaft 36 below the housing 46 and is provided therein with a reciprocable piston 86 provided with a piston rod 88 which projects upwardly therefrom through the hollow interior of the shaft 36 in which it is slidably received. The lower end of the cylinder 84 is provided with an axial projection 90 on which is rotatably mounted a pair of hollow slip rings 92 and 94, respectively. A passage 96 connects the interior of the slip ring 92 with the interior of the cylinder 84 below the piston 86 and a series of passages 98 connect the hollow interior of the slip ring 94 with the interior of the cylinder 84 above the piston 86. Pipes 100 and 102 connect the interior of the slip rings 92 and 94, respectively, with a conventional form of control valve mechanism indicated generally at 104 and by means of which air may be introduced into and/or exhausted from the opposite sides of the piston 86 in order to effect its reciprocation in the cylinder 84.

A head 110 is relatively non-rotatably secured to the shaft 36 immediately above the table 30 and fixed to the upper face of the head 110 is a forming die 112 in the present instance shown as of ring-like or loop-like formation. It will be understood that the peripheral shape of the forming die 112 as viewed in plan view substantially corresponds to the shape of the desired finished article. Accordingly, it will be understood that in the case of the particular article which it is here assumed the apparatus is designed to form the plan view of the forming die 112 will correspond to the shape of the garnish molding shown in Fig. 4 with the following difference only. Inasmuch as one end of the strip which forms the garnish molding 10 shown in Fig. 4 is provided with a tongue 120 adapted to be received in a corresponding slot formed in the opposite end of the strip so as to hold these free ends against displacement in service, the tongue will overlap the opposite end of the strip during the formation of the molding and, accordingly, in such case the peripheral surface of the forming die 112 corresponding with the straight end portion of the garnish molding carrying the tongue 120 is somewhat inclined inwardly as is illustrated at 122 in Fig. 2 so that the free ends of the strip will be offset from one another when initially formed. It will be understood that the molding 10 is of sufficient resiliency to permit the tongue 120 to be sprung into its corresponding groove in the opposed free end of the moulding after it has been bent to the shape shown. The outer peripheral edge face of the forming die 112 is shaped in a manner complementary to one face of the garnish molding 10, in the particular instance shown, to the lefthand face as viewed in Fig. 5 and so that when the molding is applied thereto the flange 26 will overlie the upper marginal face of the die 112 as illustrated best in Fig. 1.

A head 130 of approximately the same peripheral shape as the die 112 is non-rotatably secured to the piston rod 88 above the die 112 as best shown in Fig. 1. A clamping ring 132 of approximately the same size and shape as the die 112 is fixed to the lower face of the head 130 in complementary relationship with respect to the die 112. A pair of pins 134 arranged in axially parallel relation with respect to the piston rod 88 and shaft 36 are fixed in the head 130 and project downwardly therefrom and are slid-

ably received in complementary openings formed therefor in the head 110 so as to cause equal rotation of the die 112 and pressure ring 132 at all times without restricting relative axial movement between them.

As best illustrated in Figs. 1 and 2 the upper face of the table 30 is provided with a trough-like depression 140 formed therein and disposed in a radial relation with respect to the shaft 36 and in the bottom of this depression 140 a pair of spaced ways 142 are formed. A head 144 is slidably received upon the ways 142 for reciprocable movement in a direction radially of the shaft 36. The head 144 has fixed therein a pair of vertically spaced forwardly projecting pins 146 and 148 upon the forwardly projecting ends of which is supported a second head 150 arranged for pivotal movement around the vertically directed pin 152 provided for securing the head 150 to the projecting ends of the pins 146 and 148. If desired a coiled spring such as 154 may be maintained under tension between the pin 152 and a second pin 156 secured to the head 144 so as to set up sufficient friction in the pivotal connection between the heads 144 and 150 to prevent entirely free pivotal movement of the head 150, as well as to take up any play between these parts. The upper forward edge of the head 150 has fixed thereto a die member 160 in the form of a bar, the forward face of which is formed to a shape complementary to the righthand face of the garnish molding 10 as viewed in Fig. 5.

The heads 144 and 150 are reciprocable relative to the ways 142 by means of a piston 164 working in a cylinder 166 located at the righthand side of the machine as viewed in Figs. 1 and 2. The cylinder 166 is supported by being secured to a bracket 168 secured to the righthand edge of the table 30 as viewed in Figs. 1 and 2 and is positioned co-axially of the pin 148 and parallel with the ways 142. The piston 164 is provided with a piston rod 170 which projects out the lefthand end of the piston 166 and through the bracket 168 and is received within a sleeve coupling 172 in which the righthand end of the pin 148 is also received. The adjacent ends of the pins 148 and of the piston rod 170 are secured to the sleeve 172 by means of pins 174, the connection being such as to preferably permit a slight amount of universal movement between the pin 148 and the piston rod 170. The axial position of the piston 164 and the cylinder 166 is controlled by means of air introduced into and exhausted from opposite ends of the cylinder 166 through pipes 176 leading to the same air control valve 104 that controls the cylinder 84 previously described. A pair of control buttons 178 positioned on the top of the bracket 168 are suitably connected with the valve 104 in a conventional manner so that one of the buttons 178 controls the operation of the piston 86 and the other thereof controls operation of the piston 164.

A control button 180 also located on the top of the bracket 168 is provided for starting the motor 60 and although it may also be employed for stopping the motor 60 it is preferable to have some automatic means for stopping the motor 60 and consequently the rotating head 110 including the forming die 112 at a predetermined point in their rotation upon completion of each cycle of operation. Accordingly, in order to effect this last result a cam member 182, shown in Fig. 1, is secured to a side of the cylinder 84 and a cut-out switch 184 suitably connected to both the motor 70

60 and the control button 180 is secured in fixed relation with respect to the housing 46 by means of elongated brackets 186. The cut-out switch 184 is provided with an operating member 188 disposed in the path of travel of the cam 182 so that each time the cylinder 84 makes one revolution the cam 182 will strike the operating member 188 and open the circuit to the motor 60, it being understood that such circuit may be manually closed by operation of the button 180. It will, of course, be also understood that the cam 182 and cut-out switch 184 are so arranged with respect to the position of rotation of the forming die 112 that the machine will come to rest 10 with the forming die in a loading position.

15 In the operation of the above machine the stock to be acted upon to form the garnish molding 10 will be received at the machine as a straight strip of material of the cross-sectional configuration illustrated in Fig. 5 and it is the function of the machine to form such strip of material into the shape illustrated in Fig. 4. It will also be understood that the view illustrated in Fig. 2 shows the machine after the forming die 20 112 has traveled through approximately 90° of movement during a forming operation and that in actual practice the straight but inclined portion 122 will be facing and opposed to the operative face of the die member 160. With the machine in the last mentioned position the operator will have operated the control buttons 178 so as to withdraw the heads 144 and 150 to the right as viewed in Figs. 1 and 2 preferably to the extent of their movement and so as to raise the 25 piston 86, head 130 and pressure ring 132 to their fullest extent. The operator will then insert a straight strip of stock between the die 160 and forming die 112 in such a manner that the one face of the strip will lie in complementary relation with respect to the peripheral forming face of the die 112. In the case of the particular die 112 shown the strip will be inserted to such an extent that its tongued end will substantially abut against the radially directed shoulder at the inner end of the inclined portion 30 122 of its periphery and in which position the tongue 120 may be slipped over a pin 190 secured in the peripheral face of the die 112 and which tongue 120 is apertured to receive it. The pin 190 thus acts as a locating stop for the strip of stock as well as serves to hold this end of the strip of stock against pulling away from or moving relative to the die 112 during the forming operation. The operator then operates the proper 35 button 178 to move the heads 144 and 150 to the left as viewed in Figs. 1 and 2 and so that the die member 160 will contact the corresponding face of the strip in complementary relation with respect thereto and press it firmly against the peripheral face of the forming die 112. At the same time or immediately thereafter he will operate the other button 178 so as to move the piston 86 downwardly in the cylinder 84, thus drawing the pressure ring 132 downwardly against the upper flange 26 of the strip and yieldingly 40 but firmly clamp it down against the upper face of the forming die 112. The button 180 is then operated to start the motor 60 which immediately starts rotation of the forming die 112 and as it rotates it carries the strip around with it, and as it rotates the die member 160 yieldingly 45 presses the strip against the periphery of the forming die 112 and causes it to assume a shape corresponding to the shape of the periphery of the die 112.

50

55

60

65

70

75

It will be observed that because of the varying radial distances of various portions of the periphery of the die 112 with respect to the axis of the shaft 36 it will be necessary for the heads 144 and 150 with the die member 160 to advance toward and recede from the axis of the shaft 36 during rotation of the die 112 and in the present case this is taken care of by the die 112 forcing these parts back against the pressure of the air in the cylinder 166 by a camming action during 10 certain phases of rotation and by the pressure of the air in the cylinder 166 causing these parts to move inwardly to maintain their operative relation with respect to the periphery of the die 112 during other phases of operation. Thus it 15 will be noted that although this apparatus permits the die member 160 to move inwardly and outwardly to accommodate the irregularities in the radial distances of various portions of the die 112 from its axis of rotation, nevertheless the 20 die member 160 is constantly pressed against the periphery of the die member 112 with a constant force during every phase of rotation of the die member 112 during the forming process. The piston 86 holds the pressure ring 132 downwardly 25 so as to clamp the flange 26 between it and the top face of the die 112 during the forming operation and thereby prevents it from wrinkling or otherwise deviating from its true and intended form. Likewise the flange 28 is held between the 30 cooperating faces of the die members 112 and 160 and is likewise maintained against distortion. Due to the fact that the cooperating faces of the die member 112 and the die member 160 are complementary to the opposite faces of the 35 strip being acted upon at the moment such strip is being bent and the flanges at the opposite edges of the strip are held against distortion from their intended form, it is impossible for the metal of the strip during the bending operation to distort out of its true and intended form and consequently the cross-sectional configuration of the molding 10 in final form will be identical to its cross-sectional configuration in the straight strip of stock from which it is formed. 40 For this reason distortion of the metal of the strip is effectively prevented and no wrinkles or other blemishes of the strip appear in the finished product. It will also be understood that the strip of stock which is initially fed into the device is of exactly the correct length required 45 in the finished product and that when the machine has made a complete revolution so as to entirely complete the forming of the shape of the molding the cam 182 will cause actuation of the cut-out switch 184 and the machine will come to rest, whereupon the operator may operate the buttons 178 to withdraw the pistons 86 and 164 upon which the finished molding may be lifted 50 off of the die 112, the tongue 120 inserted in its cooperating slot in the opposed free end of the strip, and the article thus completed except for applying a suitable finishing coating of paint or the like where necessary or desirable.

55 Formal changes may be made in the specific embodiment of the invention described without departing from the spirit or substance of the broad invention, the scope of which is commensurate with the appended claims.

60 What we claim is:

65 1. In apparatus for bending a straight strip of metal stock, having a main body portion and a flanged edge portion, into a predetermined shape of non-circular outline including, in combination, a die member having a peripheral face 70

75

- of non-circular conformation corresponding approximately to the conformation desired in the final product, means for rotating said die member, the peripheral face of said die member being shaped in cross-section complementary to the cross-sectional configuration of one face of said strip, a portion of said die member adjacent the periphery being substantially straight and at an angle to the peripheral face, yieldable means 5 movable axially with respect to said die member having a portion substantially parallel to said last-named portion operable to yieldably clamp the flange of said strip between it and said portion of said die member, a head movable in an 10 approximately radial direction with respect to the axis of rotation of said die member, a second die member carried by said head and provided with a face the cross-sectional configuration of which is complementary to that face of said strip which 15 is not adapted to engage the peripheral face of the first mentioned die-member, and means yieldable under the camming action between said die members constantly urging said second die member towards said first die member during operative periods of said apparatus. 20
- 25 2. Apparatus of the type described including, in combination, a hollow shaft, means for rotating said shaft, a head fixed to said shaft for
- rotation therewith, a die member fixed to said head for rotation therewith, a rod slidable in said shaft, a clamping head secured to said rod beyond that end of said shaft supporting said die member, a piston secured to said rod at the opposite end of said shaft, a cylinder fixed to said shaft for rotation therewith and cooperating with said piston, means for introducing and exhausting fluid from opposite sides of said piston during rotation of said cylinder, a head mounted 10 for slidable movement in a direction approximately radial with respect to said shaft, a second die member carried by said head in cooperative relation with respect to the periphery of the first mentioned die member, a piston connected with said head, a cylinder receiving said piston, and means for introducing and exhausting fluid from opposite sides of the last mentioned piston whereby to cause said head to be advanced toward or retracted from the first mentioned die member, said piston being yieldable in said cylinder under a camming action between said die members whereby said head may advance and retract with respect to the first mentioned die member while being constantly urged toward said first mentioned die member. 25

CLARENCE P. CHAMBERLIN.
